CAN-LINING MACHINE.

1,160,965.

Specification of Letters Patent. Patented Nov. 16, 1915.

Application filed April 3, 1915. Serial No. 19,019.

To all whom it may concern:

Be it known that I, CHARLES H. WORKMAN, a citizen of the United States, residing in the city and county of San Francisco and State of California, have invented new and useful Improvements in Can-Lining Machines, of which the following is a specification.

This invention relates to a can lining machine.

In the manufacture of certain grades or varieties of canned tamales or other edibles, it is necessary to line the interior of the can with a dough-like material. This has heretofore been accomplished by hand operation and is consequently more or less unsatisfactory as it is not only unsanitary but the lining thus formed generally varies in thickness which is also objectionable.

One of the objects of the present invention is to provide a simple, substantial, sanitary machine which is automatic in operation, through which the cans are fed and by which they are partly filled and lined; the lining thus produced being of uniform thickness and density.

Further objects will hereinafter appear.

The invention consists of the parts and the construction and combination of parts as hereinafter more fully described and claimed, having reference to the accompanying drawings, in which—

Figure 1 is a perspective view of the machine which is partly broken away to show the construction. Fig. 2 is a sectional view taken through the three cylinders comprising the filling and lining magazine, showing the plungers and auger in the upward or unoperated position. Fig. 3 is a view similar to Fig. 2, showing one plunger filling a can, another plunger entering a partially filled can and forcing the material against the sides of the can, and showing the auger entering and removing the surplus lining material from a can. Fig. 4 is a section taken on line 4—4, Fig. 3, showing the filling tube and plunger drawing a charge, by vacuum means, from the feed receptacle. Fig. 5 is an enlarged sectional view of a lined can after the operations of the machine have been completed thereon.

More particularly described, A indicates a suitably shaped platform or table upon which is mounted a standard 2. Journaled

at one end of said table is a main drive shaft 3, to which power is transmitted through a pulley 4 from any suitable source not here shown. Mounted on one side of the standard 2 is a hopper 5. The dough with which the cans are lined is deposited in this hopper and is delivered in measured quantities to each can successively by means hereinafter to be described.

The cans are conveyed through the machine by any suitable means, but preferably by a chain, such as indicated at 6, upon which is mounted a plurality of projecting lugs or arms 7 which are adapted to engage the cans and feed same through the machine. The chain is intermittently moved by a ratchet mechanism, generally indicated at 8, from a pivotally mounted rocker-arm 9, which in turn is operated by a link 10 connected with a crank 11 secured upon a secondary drive shaft 12 which is driven by the main drive shaft through bevel-gears, indicated at 13, said shaft being suitably supported below the table at right angles to the drive shaft. The intermittent movement of the chain or can feeding device will cause the cans to be intermittently moved and a single can being fed through the machine will be brought into register, first, with the cylinder 14, second, with the cylinder 15, and, third, with the cylinder 16; the three cylinders 14, 15 and 16 being the filling, forming and trimming cylinders respectively. The cylinder 14 is in this instance connected with the main dough receiving hopper by means of a horizontally disposed cylinder 17; this cylinder having an opening in its upper side which registers with the interior of the hopper.

Mounted in the cylinder 17 is a piston or plunger 18 which is reciprocated at timed intervals by means of a pivotally mounted rocker-arm 19, one end of which is operated by a roller 19^a which engages with an internal cam 20 formed in the wheel 21 which is secured upon and driven by the secondary drive shaft. The other end of the rocker-arm is connected with the piston or plunger 18 by means of an offset link 22.

Mounted in cylinder 14 is a plunger 23. This is reciprocated at timed intervals by means of a pivotally mounted rocker-arm 24 which is operated by means of an arm 25, on the lower end of which is mounted a roller

26, said roller engaging with an internal cam 27 formed in the wheel 21 on the face opposite to cam 20. The lower end of the arm, below the roller, is preferably fork-shaped, as indicated at 28, to straddle the shaft and also to guide the arm in its up and down movement. The opposite end of rocker-arm 24 is connected with the plunger 23 by means of a link 29. The position of cams 20 and 27 in wheel 21 is such that plunger 23 will be lifted by rocker-arm 24 when plunger 18 is being moved inwardly toward the cylinder 14 by means of the rocker-arm 19. When the reverse movement takes place plunger 23 will assume the position indicated in Fig. 4 and will in this manner close the opening between cylinders 17 and 14 or act as a valve so that as piston 18 moves outward a sufficient vacuum will be produced in the cylinder to draw a quantity of dough from the hopper into the interior of cylinder 17, as indicated at 30.

The reverse movement of the two plungers will cause plunger 23 to clear the opening between cylinders 14 and 17 and will thus permit plunger 18 to force out the quantity of dough 30 previously delivered, into cylinder 14. The reverse movement of the plungers again will cause the plunger 23 to force this quantity of dough into the can and will at the same time act as a valve to close the communicating opening between the cylinders, permitting vacuum to be formed in cylinder 17 and a new charge of dough to enter. The operation between the two cylinders is thus automatic and co-operative and a uniform quantity of dough will in this manner always be delivered to the can.

40 The downward movement of the plunger 23 takes place while a can is positioned directly under the lower discharge end of cylinder 14 or while the can is remaining stationary. The plunger 23 will move up while the can is being fed to the second position below cylinder 15. A forming plunger 31 mounted in said cylinder will then move down into the body of the can, as indicated in Fig. 3, and being of less diameter than the can will force the dough upwardly and outwardly and partly form or line the dough within same. This plunger is operated by means hereinafter to be described.

55 The third movement of the can will bring it into register with cylinder 16 where the trimming or finishing operation takes place and this is accomplished as follows: The can in this position will be supported upon a lifting platform 32 in the form of a plunger 60 which is operated by means of a cam 33 engageable with a roller 34, mounted on the lower end of the plunger. This plunger raises the cam into the position indicated in Fig. 3 where the lower end of cylinder 16 65 enters the can; a shoulder 35, near the end

of the cylinder, forming a stop and joint at this point to prevent any escape of the dough while the dough is being trimmed and shaped and while any superfluous amount of same is being removed.

The trimming, shaping and removing of the dough is accomplished by means of an auger 36 secured upon the end of a shaft 37 journaled in an extension arm 2^a formed on standard 2. This shaft is continuously revolved by means of shafts 38 and 39 suitably journaled on the standard and gears 40, 41 and 42. The auger is also reciprocated, that is, it is raised and lowered, with relation to the interior of the can, as indicated in Figs. 2 and 3, and this is accomplished as follows: Secured upon shaft 37 is a grooved collar 43. Engageable with said collar is a pair of pins or rollers 44 mounted in the outer fork-shaped end 45 of a pivotally mounted rocker-arm 46. The other end of said arm is connected by a rod 47 with an internal cam 48. A collar 49 mounted near the lower end of the rod and engageable with cam 48 causes the rod to transmit reciprocal movement through the rocker-arm 46 to shaft 37, consequently raising or lowering auger 36 with relation to the can face. The forming plunger 31, mounted in cylinder 15, is raised and lowered in unison with the auger by means of a link 50 secured at one end to the plunger and at its other end to a pin 51 mounted on one side of fork 45. The lowering movement of the auger 36 transmitted through cam 48, rod 47 and rocker-arm 46, and the revolving movement transmitted to same through shafts 38 and 39, with connected gears, causes the auger to trim the lining material which has already been partly formed by the plunger 31 and any superfluous material thus removed is elevated by the auger to the upper end of cylinder 16 where it is forced through an opening 52 into a tube 52' which connects with the hopper 5. Any superfluous dough delivered to the can is thus automatically returned to the hopper where it is delivered to cans as they are successively fed through the machine.

115 The plungers 29 and 31, together with the 116 auger 36, are all depressed in unison; this movement being controlled by the position of the respective connected operating cans. The position of cam 33, which operates the can lifting platform under cylinder 16, is 120 such that the can will be raised into position with cylinder 16 just before the auger is lowered. No leakage or escape of dough will thus take place.

125 Referring to Figs. 2 and 3, it will be seen that the forming plunger 31 is hollow and that the lower end of same is closed by a valve 60. This valve is mounted upon the end of a stem 61 which extends through the plunger. The upper end of the plunger is 130

slotted and a pin 62 extends through the rod 61 and the slots in the plunger, said slots being sufficiently elongated to permit the valve to open, as shown in Fig. 2. The valve is 5 provided for the purpose of relieving any vacuum interior of the can when the forming plunger is raised, and the valve is automatically opened into the position shown in Fig. 2 when the plunger is raised as it has 10 a tendency to adhere to the dough-like material in the can; the opening movement of the valve being limited, however, by the length of the slots through which pin 62 extends. The vacuum in the inside of the 15 can is thus relieved and the dough is prevented from being withdrawn with the plunger.

A machine constructed as here shown is automatic in operation and needs very little 20 attention, as the cans are fed therethrough by means of the chain feeding mechanism previously described. The machine is, furthermore, sanitary, as the hopper, together with the connected feeding, forming and 25 trimming cylinders are so positioned that they may be readily cleaned from time to time. Only one attendant is necessary where a machine of this type is used and his only duty will be to see that the hopper is supplied 30 from time to time with a sufficient quantity of dough; everything else being automatically attended to by the machine.

The materials and finish of the several 35 parts of the machine are such as the experience and judgment of the manufacturer may dictate.

I wish it understood that various changes 40 in form, proportions and minor details of construction may be resorted to within the scope of the appended claims and that I do not wish to limit myself to the specific design and construction here shown.

Having thus described my invention, what 45 I claim and desire to secure by Letters Patent—

1. A can lining machine comprising, in combination, means for delivering a quantity of dough to a can, and means for spreading said dough evenly over the interior surface 50 of the can and means for trimming the inner face of the lining.

2. A can lining machine comprising, in combination, means for delivering a quantity of dough to a can, means for spreading the 55 dough inside of the can to form a lining for the can, and means for trimming the inner face of the lining and removing any surplus dough from the can.

3. In a can lining machine, in combination, a hopper for supplying dough to a can, means for spreading the dough over the interior surface of the can to form a lining, and means for reducing the thickness of the 60 dough lining subsequent to the spreading operation.

4. In a can lining machine, in combination, a hopper for supplying dough to a can, means for spreading the dough over the interior surface of the can, and trimming means adapted for trimming the interior 70 surface of the lining.

5. In a can lining machine, means for supplying dough to a can, means for spreading the dough over the interior surface of the can to a certain thickness, and means for trimming the lining and reducing its thickness. 75

6. A can lining machine comprising, in combination, a receiving hopper for dough, said hopper having a discharge opening 80 formed therein, a receiving cylinder connected with said opening, a discharge cylinder connected with the receiving cylinder, means for automatically feeding a can to a point below the discharge cylinder in register 85 with same, means for conveying the dough from the receiving cylinder to the discharge cylinder, means for forcing the dough out of the discharge cylinder into the can, means for spreading the dough inside of the can to 90 form a lining for the can, and means for trimming the dough and removing any surplus dough from within the can.

7. In a can lining machine, a hopper for supplying dough to a can, a forming plunger, mechanism for forcing the plunger into the can to spread the dough over the interior surface of the can for forming a lining, and a trimmer insertible in the can for trimming the lining. 95

8. A can lining machine comprising, in combination, a receiving hopper for dough, a cylinder mounted below said hopper having an opening formed therein communicating with the interior of the hopper, means for producing a sufficient degree of vacuum within said cylinder to draw a charge of dough from the hopper into the cylinder, means for discharging the dough from the cylinder into a can, means for spreading the dough inside of the can to form a lining for the can, and means for trimming and removing any surplus dough from within the can. 105

9. A can lining machine comprising, in combination, a receiving hopper for dough, means for discharging a measured quantity of dough from the hopper into a can, means for spreading the dough inside of the can to form a lining for the can, and means for reducing the lining thickness and removing any surplus dough from the can. 115

10. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the plunger 125 into the cylinder, 130

ger into the can to spread the dough evenly over the interior surface of the can to form a lining, and means for reducing the lining thickness and removing any surplus dough from the can subsequent to the spreading operation.

11. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the plunger into the can to spread the dough evenly over the interior surface of the can, and means for trimming and removing any surplus dough from the can, said means comprising a second cylinder and an auger rotatively and reciprocally mounted in said cylinder.

12. A can lining machine comprising, in combination, a receiving hopper for dough, said hopper having a discharge opening formed therein, a receiving cylinder connected with said opening, a discharge cylinder connected with the receiving cylinder, means for automatically feeding a can to a point below the discharge cylinder in register with same, means for conveying the dough from the receiving cylinder to the discharge cylinder, means for forcing the dough out of the discharge cylinder into the can, means for spreading the dough inside of the can to form a lining for the can, means for trimming any surplus dough from the inner face of the lining, and means for returning said surplus dough to the hopper.

13. In a can lining machine, a trimming cylinder, adapted to be received by a can, a can support movable to carry the can thereon toward the cylinder to receive the latter, and a trimmer within the cylinder and movable into the can.

14. A can lining machine comprising, in combination, a receiving hopper for dough, a cylinder mounted below said hopper having an opening formed therein communicating with the interior of the hopper, means for producing a sufficient degree of vacuum within said cylinder to draw a charge of dough from the hopper into the cylinder, means for discharging the dough from the cylinder into a can, means for spreading the dough inside of the can to form a lining for the can, means for trimming and removing any surplus dough from within the can, and means for returning said surplus dough to the hopper.

15. A can lining machine comprising, in combination, a receiving hopper for dough, means for discharging a measured quantity of dough from the hopper into a can, means for spreading the dough inside of the can to

form a lining for the can, means for trimming the lining surface and removing any surplus dough from the can, and means for returning said surplus dough to the hopper.

16. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the plunger into the can to spread the dough evenly over the interior surface of the can, a return conduit leading to the hopper, and unitary means for trimming any surplus dough from the can and delivering the surplus to the return conduit.

17. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the plunger into the can to spread the dough evenly over the interior surface of the can, means for trimming and removing any surplus dough from the can, said means comprising a second cylinder with which the can is brought into register after the forming plunger has been withdrawn, an auger mounted in said cylinder, means for rotating said auger, and means for reciprocating the auger to permit it to be raised and lowered in the can to trim off any surplus dough.

18. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the plunger into the can to spread the dough evenly over the interior surface of the can, means for trimming and removing any surplus dough from the can, said means comprising a second cylinder with which the can is brought into register after the forming plunger has been withdrawn, an auger mounted in said cylinder, means for rotating said auger, means for reciprocating the auger to permit it to be raised and lowered in the can to trim off any surplus dough, an extension on the end of the second cylinder fitting the interior of the can, a lifting platform below the cylinder upon which the can rests when in register with the cylinder, and means for raising said platform to per-

mit the extension on the cylinder to enter the upper end of the can when the auger is lowered to trim the dough lining of the can.

19. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the plunger into the can to spread the dough evenly over the interior surface of the can, 10 means for trimming and removing any surplus dough from the can, said means comprising a second cylinder with which the can is brought into register after the forming plunger has been withdrawn, an auger 15 mounted in said cylinder, means for rotating said auger, means for reciprocating the auger to permit it to be raised and lowered in the can to trim off any surplus dough, and means for returning said surplus dough to 20 the hopper.
20. A can lining machine comprising, in combination, a receiving hopper for dough, means for discharging a measured quantity of dough from the hopper into a can, a cylinder, means for automatically feeding the can to a point in register with the mouth of said cylinder, a forming plunger of smaller diameter than the interior of the can mounted in the cylinder, means for forcing the 25 plunger into the can to spread the dough evenly over the interior surface of the can, means for trimming and removing any surplus dough from the can, said means comprising a second cylinder with which 30 the can is brought into register after the forming plunger has been withdrawn, an auger mounted in said cylinder, means for rotating said auger, means for reciprocating the auger to permit it to be raised and lowered 35 in the can to trim off any surplus dough, an extension on the end of the second cylinder fitting the interior of the can, a lifting platform below the cylinder upon which the can rests when in register with 40 the cylinder, means for raising said platform to permit the extension on the cylinder to enter the upper end of the can when the auger is lowered to trim the dough lining of the can, and means for returning said 45 surplus dough to the hopper.

21. A can lining machine comprising, in combination, a receiving hopper for dough, said hopper having a discharge opening formed therein, a receiving cylinder connected with said opening, a discharge cylinder connected with the receiving cylinder, means for automatically feeding a can to a point below the discharge cylinder in register with same, a plunger mounted in the receiving cylinder to draw the charge from 50

the hopper into the cylinder and also to force the dough thus admitted into the discharge cylinder, a plunger in the discharge cylinder to force the dough into the can, a second cylinder with which the can is 55 brought into register after receiving the dough from the discharging cylinder, a forming plunger on said cylinder, means for forcing said plunger into the can to spread the dough interior of the can to form a lining for same, a third cylinder with which the can is brought into register after the forming plunger is withdrawn from the can, an auger in said cylinder, means for 60 rotating said auger, and means for reciprocating the auger to permit it to be raised and lowered in the can to trim off any surplus dough.

22. A can lining machine comprising, in combination, a receiving hopper for dough, said hopper having a discharge opening formed therein, a receiving cylinder connected with said opening, a discharge cylinder connected with the receiving cylinder, means for automatically feeding a can to a point below the discharge cylinder in register with same, a plunger mounted in the receiving cylinder to draw the charge from the hopper into the cylinder and also to force the dough thus admitted into the discharge cylinder, a plunger in the discharge cylinder to force the dough into the can, a second cylinder with which the can is 65 brought into register after receiving the dough from the discharging cylinder, a forming plunger on said cylinder, means for forcing said plunger into the can to spread the dough interior of the can to form a lining for same, a third cylinder with which the can is brought into register after the forming plunger is withdrawn from the can, an auger in said cylinder, means for rotating said auger, means for reciprocating the auger to permit it to be raised and lowered 70 in the can to trim off any surplus dough, an extension on the end of the second cylinder fitting the interior of the can, a lifting platform below the cylinder upon which the can rests when in register with the cylinder, and means for raising said platform to permit the extension on the cylinder to enter the upper end of the can when the auger is lowered to trim the dough lining of the can.

23. A can lining machine comprising, in combination, a receiving hopper for dough, said hopper having a discharge opening formed therein, a receiving cylinder connected with said opening, a discharge cylinder connected with the receiving cylinder, means for automatically feeding a can to a point below the discharge cylinder in register with same, a plunger mounted in the receiving cylinder to draw the charge from the hopper into the cylinder and also to force the dough thus admitted into the discharge cylinder to force the dough into the can, a second cylinder with which the can is 80 brought into register after receiving the dough from the discharging cylinder, a forming plunger on said cylinder, means for forcing said plunger into the can to spread the dough interior of the can to form a lining for same, a third cylinder with which the can is brought into register after the forming plunger is withdrawn from the can, an auger in said cylinder, means for rotating said auger, and means for reciprocating the auger to permit it to be raised and lowered 85 in the can to trim off any surplus dough.

charge cylinder, a plunger in the discharge cylinder to force the dough into the can, a second cylinder with which the can is brought into register after receiving the dough from the discharging cylinder, a forming plunger on said cylinder, means for forcing said plunger into the can to spread the dough interior of the can to form a lining for same, a third cylinder with which the can is brought into register after the forming plunger is withdrawn from the can, an auger in said cylinder, means for rotating said auger, means for reciprocating the auger to permit it to be raised and lowered in the can to trim off any surplus dough, and means for returning said surplus dough to the hopper.

24. A can lining machine comprising, in combination, a receiving hopper for dough, said hopper having a discharge opening formed therein, a receiving cylinder connected with said opening, a discharge cylinder connected with the receiving cylinder, means for automatically feeding a can to a point below the discharge cylinder in register with same, a plunger mounted in the receiving cylinder to draw the charge from the hopper into the cylinder and also to force the dough thus admitted into the discharge cylinder, a plunger in the discharge cylinder to force the dough into the

can, a second cylinder with which the can is brought into register after receiving the dough from the discharging cylinder, a forming plunger on said cylinder, means for forcing said plunger into the can to spread the dough interior of the can to form a lining for same, a third cylinder with which the can is brought into register after the forming plunger is withdrawn from the can, an auger in said cylinder, means for rotating said auger, means for reciprocating the auger to permit it to be raised and lowered in the can to trim off any surplus dough, an extension on the end of the second cylinder fitting the interior of the can, a lifting platform below the cylinder upon which the can rests when in register with the cylinder, means for raising said platform to permit the extension on the cylinder to enter the upper end of the can when the auger is lowered to trim the dough lining of the can, and means for returning said surplus dough to the hopper.

In testimony whereof I have hereunto set my hand in the presence of two subscribing witnesses.

CHARLES H. WORKMAN.
